UNITED STATES PATENT OFFICE.

FRANK MARION, OF HARDWICK, VERMONT, ASSIGNOR OF SEVENTEEN TWENTY-FOURTHS TO FRANK T. TAYLOR AND ONE-TWELFTH TO V. W. RAND, BOTH OF HARDWICK, VERMONT.

ROTARY ENGINE.

1,219,829.

Specification of Letters Patent. Patented Mar. 20, 1917.

Application filed October 18, 1914. Serial No. 866,571.

To all whom it may concern:

Be it known that I, FRANK MARION, a citizen of the United States, residing at Hardwick, in the county of Caledonia and State of Vermont, have invented certain new and useful Improvements in Rotary Engines, of which the following is a specification.

The invention has for an object to give 10 an improved construction of rotor piston and abutment in the type of engine illustrated which will be adapted to use in an internal combustion engine, and will coöperate in a manner of peculiar advantage when used with steam, as well. A further object 15 is to provide a desirable construction of inlet for operating fluid. It is also a purpose to provide a packing of an efficient character for use in engines of this construction.

20 An important object is to give a compact construction whereby the various elements required in such an engine may be actuated with a minimum of operative connections, and readily accessible for adjustment and 25 repair. Additional objects and advantages will appear, some of which will be apparent from the following description of one embodiment of my invention, and from the drawings thereof, in which,

30 Figure 1 is an elevation of one side of the device with the cover plate removed.

Fig. 2 is a rear elevation thereof.

Fig. 3 is a view from one side at right angles to the first two figures.

35 Fig. 4 is a similar view from the opposite side.

Fig. 5 is a detail section of the abutment showing the packing means.

40 Fig. 6 is a similar view of the packing device in the piston.

There is illustrated an engine comprising a circular base plate 10 upon which there is carried the body casting 11, the front and back sides of which are planed and parallel, 45 a large circular chamber 12 being formed in the upper part thereof, below which there is a smaller circular chamber 13, the centers of the chambers being so located that their boundaries intersect, whereby communication 50 is formed between the chambers for a purpose which will appear. The inner faces of these chambers are smoothly finished, and concentric with the chambers a suitable water space 14 is formed in the casting 11 open

on each side, and having suitable inlet and 55 outlet, 15 and 16. The casting 11 is concentric at the upper part with the chamber 12, and for closing the chamber and water spaces front and back plates 17 and 18 are provided, conforming to the shape of the 60 casting 11 and bolted thereto in a suitable way. These plates are provided with suitable bearings 19 and 20, concentric with the chambers 12 and 13 respectively, in the upper of which there is mounted the main 65 shaft 21 and the lower of which support the tubular shaft 22. Carried by the shaft 21 there is a piston 23 having a cam surface 24 of gradually increasing radius terminating in an abrupt extension or head 25, the outer 70 part of which is disposed to lie close to the perimetral face of the chamber 12 and parallel therewith for a short distance. The piston corresponds in thickness to the thickness of the casting 11 from front to back. 75 The piston may be solid or hollowed out suitably for lightness. The head 25 is provided with a transverse groove 26 across its outer face, from which extensions 27 are formed, disposed radially of the piston on 80 each side. Set in these grooves there are two right angled packing plates 28, each having one of its arms fitted snugly in a respective groove extension 27, while the other extends across the head 25 in the 85 grooves 26 a little more than half way, the adjacent portions of the outer arms being mortised in overlapping relation, as shown at 29. At the junctions of the groove 26 and its extension diagonal seats 30 are formed, 90 in which springs 31 are set bearing outwardly on the plates 28, whereby they are simultaneously borne against the lateral and perimetral surfaces of the chamber. Carried by each of the plates 17 and 18, there 95 are concentric packing rings 32 fitted in suitable grooves in the plates, having suitable springs therebehind bearing them outwardly against the piston, and being closely adjacent or overlapping the inner arms of 100 the plates 28. These rings are preferably split, with mortised overlapped ends, as at 33. The work side 34 of the head 25, the one against which the gases or fluid act to rotate the piston, is curved outward beginning closely adjacent the groove 26, this curve being suited to the proposed speed of 105 the engine. The shaft 22 is tapered through-

out that portion projected through the chamber 13, whereby it may be adjusted to compensate for wear with an oscillating abutment block 35, revolvable thereon, and fitting snugly in the chamber 13. The shaft 22 is held in place by a nut 36 engaged thereon outwardly of the tapered portion and bearing against the plate 18.

The block 35 is recessed at its lower part, 10 and has engaged therewith a spring 37 extending tangentially therefrom and anchored to the casting 11 by a screw 38 which may be adjusted from the exterior. The block is cut away at its upper side to form a 15 recess 39 having a curved face formed and arranged to aline with the outer face of the chamber 12 at times, concentric therewith. The radius of the chamber 13 is greater than the distance from its center to the point of 20 minimum radius on the piston 23. Thus under action of the spring one side of the recess 39 will always bear against the piston, the direction of tension of the spring being such that the side in the direction of rotation 25 of the piston will be the one engaged.

The shaft 22 at its forward end is connected by a rotating joint to a supply pipe 40 having laterals 41 and 42, the one leading to a source of expansive fluid, and having a 30 controlling valve 43, in addition to an automatic intermittent valve 44, to be described, while the other lateral leads to a compressor tank 45, and has an interposed cut-off 46. The shaft 22 is provided with a 35 timing lever 47 by which it may be slightly rotated. A lateral port 48 is also formed therein and intermediately of the conical portion, and the block 35 has formed therein a large pocket 49 open at the inner side 40 for communication with the port 48. This pocket is slightly enlarged toward its outer end, and opens through the periphery of the block in that part which lies in the chamber 12, although a part of the pocket may be initially without the chamber 12. Across the 45 periphery of the block 35 on each side of the pocket 49 there are formed grooves 50 and connecting laterals 51, in the sides of the block, in which there are set small packing 50 plates 51' similar to the ones first described, and having similar functions, being held outwardly at all sides by means of four small helical springs 52 confined by the plates. A small pocket 53 is formed in the 55 side of the chamber 13 adjacent the point of its communication with the chamber 12 and the projected portion of the abutment, in which there is engaged from the exterior of the casing 11 a spark plug 54.

60 The curve of the work face is such that under action of the spring 37 the block 35 will bear against the work face of the piston, assisting in its rotation, and maintaining a close fit therewith throughout the action. On the opposite side of the chamber

13 from the spark plug there is formed an exhaust port 55 immediately adjacent the periphery of the chamber 12.

Communicating with the chamber 12 at a point suitably removed from the area of high compression there is a lateral duct 56 formed in the casing and having a suitable small pipe engaged therein leading to an oil cup 57, from which an oil supply pipe 58 leads to the small opening 59 in the periphery of the chamber 12 close to the abutment block. Suitable check valves 58' are incorporated in the duct and opening 59.

A large gear 60 is mounted on the main shaft immediately outward of the plate 17, 80 and also an eccentric 61, engaged with which is the rod 62, the outer end of which operates the contact lever 63 which, adjacent one limit of its movement, closes the ignition circuit by bringing one of the spaced contacts 64 of a circuit closer against the other. The details of this circuit and apparatus are not illustrated, suitable forms being familiar in the art. The eccentric is also provided with a wrist 65 adjustable in a concentric slot 66 in the eccentric and held by a nut 67 engaged in the outer end of the wrist and bearing against a sleeve 68 encircling the wrist. A link 69 is mounted removably on this wrist and connected to the lever 47. By this means the opening of the inlet port 48 may be timed to accord with the spark and speed of the engine. The spark may also be timed variously by adjustment of the screw 70 on the lever 63.

At the upper part of the plate 17 there is mounted a gear 71 meshed with the large gear 60 having a beveled outer part meshed with a bevel gear 72 in a centrifugal governor of suitable construction also mounted 105 on the plate 17, and operating the throttle valve 73 in the pipe 40.

At one side, preferably opposite the side of which the spark plug is located, a pump driving gear 74 is mounted on the plate 17 110 in mesh with the gear 60, having eccentric connection with the piston of a pump 75, by which the gas supplied at 76 is maintained at a suitable pressure in the charge tank 45, from which connection is made directly to 115 the pipe 42. The tank is provided with a safety control by which the supply valve 78 for the pump is closed when the pressure reaches a predetermined degree. At the opposite side of the motor is located a magneto 79, operated by a gear 80 meshed with the gear 60 adjacent its lowest part. The arrangement of driving gears around the gear 60 for the auxiliary apparatus is of great advantage in such engines, enabling 120 the provision of a unit power plant in a compact form and enabling the repair or removal of any of the auxiliaries without interference with the others.

In the use of the engine as an internal 130

combustion engine it is only necessary to close the valve 43 and open the one 46, and have the wrist 65 so adjusted that the shaft 22 is rotated to move the port 48 to the outer limit of its movement before occurrence of the spark, the spark timer having also been adjusted to accord with the speed desired, the engine being turned until the head 25 passes onto the block 35 which is thereby moved to bring the side of the recess 39 into alignment with the curved face of the chamber 12, and the pocket 49 alined with the port 48. The shaft 22 is being moved to cut off this communication, which cut off occurs just before the spark is made. The spark occurs just before the work face of the head passes beyond the block, and when the latter is thus released and rotated by the spring 37, the pressure of the expanding gases from the pocket 49 drives the piston. Gases in advance of the head 25 during its rotation are allowed free escape through the exhaust port. The operation of the governor to regulate the speed will be understood without explanation.

When the invention is to be used as a steam engine, the valve 46 is closed and the one 43 opened, and the necessary connections made with a source of expansive fluid. The wrist 65 is also so adjusted that the port 48 is at full opening when the block 35 springs behind the head 26, and will be operated to close at the desired time to permit full advantage to be derived from the expansive action of the fluid. The eccentricity 24 in the piston, in advance of the head 25 cooperates to this end, by moving the block 35 to carry the pocket 49 out of registry with the port 48. In fact this eccentricity may be utilized alone for that purpose, in some cases, and the automatic movement of the shaft 22 dispensed with by disconnecting the link 69 from the wrist 65.

I have thus given a construction of engine which may be constructed with great ease, which will occupy but little room and involve a minimum of expense for its installation, it being unnecessary to provide separate mountings for other devices such as the magneto, the governor, valve timer, spark timer, compressor. Also there are parts essential to its use with steam or as an internal combustion engine, which are peculiarly efficient in both applications.

In order to facilitate the tuning of the cut-off and its adaptation readily to steam or gas, the eccentric may be slotted as at 66' and a bolt 65' engaged therethrough with the main gear a nut being provided on the bolt to clamp the eccentric adjustably to advance or retard its action.

What is claimed:

1. An engine of the class described comprising a casing having a circular chamber therein, a piston revoluble concentrically

therein, and including a head engaging close against the outer side of the chamber, a second circular chamber intersecting the first, an abutment member revoluble concentrically therein formed to clear the first chamber at one position, and having a portion to bear against the piston throughout rotation of the latter, yieldable means engaged with the abutment member for engagement thereof with the piston, said head having an inclined forward face to fend the abutment member into position to clear the first chamber, a hollow duct member engaged within the abutment member, and having a lateral port opening against the inner surface of the abutment member, said abutment member having a pocket therein opening into the first chamber when the abutment member is projected into the chamber, and opening against the duct member for registration with said port at certain positions of the abutment and duct members, an ignition device in the perimeter of the second chamber adjacent the pocket for ignition of a charge therein at times, operative connections between the piston and the duct member to change the position of the port for the purposes described, including a variable stroke device, means to operate the ignition device, and fluid supply connections with the duct member.

2. In a device of the class described, a casing having a circular chamber therein, a concentrically revoluble member in the chamber having a peripheral port, circumferentially spaced transverse grooves being formed in the periphery of the member, closely adjacent the port, and on opposite sides thereof, and connecting grooves in each side of the member, four substantially L-shaped packing plates having overlapped ends slidably engaged in the grooves, and means provided whereby the plates are borne outwardly for the purposes described.

3. An engine including a piston and a chambered member receiving the piston for operation therein, means for admitting an actuating fluid to the chamber including a movable member having a passage therethrough adapted to communicate with the chamber, a rotatable duct member fitted to said movable member and having a lateral port arranged to register with the said passage at certain positions of the movable member and duct member, a rotating member operatively connected with the piston, an adjustable eccentric device thereon and operative connections between said eccentric device and the duct.

4. An engine comprising a body casting having a circular chamber therein closed on each side to form a casing, a piston revolubly mounted in the chamber, a shaft carrying the piston and having an end projecting through at least one side of the casing a

large gear carried thereby close against the casing, a plurality of spaced gears mounted on the casing and meshing with the large gears, and respective auxiliary devices fixed 5 to the casing and operatively connected with said last named gears for maintaining and controlling action of the engine.

5. In a device of the class described a casing having a circular chamber a revoluble member snugly fitted in the chamber and having a port, transverse grooves formed in the outer face of the revoluble member on opposite sides of said port, connecting grooves being formed in the side of the revo-

luble member outwardly of its axis, and packing devices each having one arm disposed in one of the transverse grooves and in a communicating connecting groove conforming to the contour of the groove, opposed ends of the packing members being in overlapped 15 relation for the purposes described.

In testimony whereof I affix my signature in presence of two witnesses.

FRANK MARION.
